UNITED STATES PATENT OFFICE.

MABELLE M. HERRINGTON, OF MOUNT VERNON, NEW YORK.

DESIGN FOR A DOLL.

Application filed September 9, 1922. Serial No. 3,661. Term of patent 3½ years.

To all whom it may concern:

Be it known that I, MABELLE M. HERRINGTON, a citizen of the United States, and a resident of Mount Vernon, in the county of Westchester and State of New York, have invented a new, original, and ornamental Design for Dolls, of which the following is a specification, reference being had to the accompanying drawings, forming part thereof, in which—

I claim:

The ornamental design for a doll as shown in the accompanying drawing.

MABELLE M. HERRINGTON.
